UNITED STATES PATENT OFFICE.

WILLIAM WEBER, OF CHICAGO, ILLINOIS.

REGISTERING-BANK.

SPECIFICATION forming part of Letters Patent No. 712,873, dated November 4, 1902.

Application filed December 9, 1901. Serial No. 85,152. (No model.)

To all whom it may concern:

Be it known that I, WILLIAM WEBER, a citizen of the United States, residing at Chicago, in the county of Cook and State of Illinois, 5 have invented certain new and useful Improvements in Registering-Banks, of which the following is a specification.

The object of this invention is the production of a locked box or receptacle into which 10 money, either in coin or paper, may be put and the amount of each deposit and the total amount of all deposits registered. Such a bank it is clear may be used as a private locked receptacle for the savings of an individual or of a household or by a banking institution as a means for increasing its savings deposits.

In the accompanying drawings, Figure 1 is a face view of this improved bank, showing 20 the front piece partly broken away to illustrate portions of the registering mechanism. Fig. 2 is a transverse vertical section through the bank on dotted line 2 2 of Fig. 1. Fig. 3 is a similar view on dotted line 3 3 of Fig. 1. 25 Fig. 4 is a rear side view of the registering mechanism, taken on dotted line 4 4, Fig. 2. Fig. 5 is a transverse section through the bank on dotted line 5 5 of Fig. 1. Fig. 6 is a fragmental vertical section on dotted line 30 6 6 of Fig. 2, showing in elevation the locking mechanism. Fig. 7 is a key for disengaging the locking mechanism. Fig. 8 is an enlarged detail showing the form of the stop A²⁰. Fig. 9 is a fragmental side elevation 35 showing the relative positions of the stop A²⁰, the wheel C, and the rod C¹⁴.

In the production of this bank I provide a receptacle A, preferably formed from sheet metal and having the integral sides and top 40 piece A', provided with the bottom flanges A², the integral bottom, and back piece A³, said bottom piece being secured to the bottom flanges A² in any suitable manner, as by means of the tubular rivets shown, the back 45 piece being provided with the side flanges A⁴ and the top flange A⁵, secured to the sides and top piece, respectively, and the front piece A⁶, of cast metal, made removable from the other parts of the receptacle. This front 50 piece is provided in its face with two openings A⁷ and A⁸, one of which openings shows the "cents" figures and the other the "dol-

lars" figures of the dials of the registering mechanism. It also has another opening A⁹, through which a push-button, to be herein- 55 after described, projects, which button it is necessary to depress before the registering apparatus can be operated. The front piece bears upon its face any suitable design, and the dollars and cents openings are suitably 60 designated thereon. The inside face of the front piece is provided at its top with a flange A¹⁰, having notches A¹¹, A¹², and A¹³ for the reception of the registering-keys, also a flange A¹⁴, having a notch A¹⁵ for holding one end 65 of a spring to be hereinafter described. At the bottom of the front piece is a flange A¹⁶, adapted to lie within the receptacle. The front piece is also provided with the raised ring A¹⁷, against which the cents-wheel bears, 70 also with the studs A¹⁸, A¹⁹, A²⁰, A²¹, A²², A²³, and A²⁴, the latter stud being internally screw-threaded to receive a correspondingly-screw-threaded pin A²⁵, adapted to extend through the receptacle to the locking device on the inside rear wall thereof. This pin is provided 75 near the end opposite to that upon which the screw-thread is formed with a conical head A²⁶ and with a groove A²⁷ just rearward of said conical head. The top of the receptacle has an 80 opening A²⁸, adapted to receive deposits, and the rear side has an opening A²⁹ for a key to disengage the locking device.

Keys B, B', and B², of spring material, bent upward and outward at their forward ends to 85 extend through the notches A¹¹, A¹², and A¹³ in the flange A¹⁰ of the front piece A⁶ and to present a surface for the fingers of the operator, are secured at their rear ends to the inner side of the rear wall of the receptacle. 90

The registering mechanism of this bank comprises a ratchet-wheel C, having one hundred teeth formed in its periphery. This wheel is rotatably mounted centrally on the front piece and on the inner side thereof 95 upon the projection A²⁸ and is provided upon its face with numbers from "0" to "99," inclusive, placed in a circular series near the periphery of said wheel. This wheel C may be called the "cents-wheel." Just within 100 the ring A¹⁷ on the inner face of the front piece A⁶ is the "dollars-wheel" C', rotatably mounted upon the stud A²³, formed integral with the front piece A⁶. The face of the

dollars-wheel bears a series of numbers from "0" to "9," inclusive, and its periphery is provided with curved depressions forming between them ten points or teeth. A projection C², formed upon the face of the cents-wheel, is adapted to engage one of the teeth upon the dollars-wheel at each revolution of the cents-wheel and to rotate said dollars-wheel the distance of one tooth, or a portion of 5 said distance, the proper movement of said dollars-wheel being completed by the action of a curved wire spring C⁸, secured at one end to the rear side of the front piece A⁶, its free end being curved to correspond with the curved depressions in the periphery of said dollars-wheel. This spring acts not only to hold said dollars-wheel from accidental rotation, but when it is turned partially by the projection C² upon the cents-wheel the movement of said dollars-wheel is completed by the action of the spring 10 in dropping into the next adjacent notch in said wheel.

A lever C⁴ is pivotally mounted upon the stud A¹⁸, formed integral with the front piece, 15 and is held upward against the flange A¹⁴ by means of the spring C⁵, one end of which lies in a notch C⁶, formed in said lever, the opposite end lying in the notch A¹⁵, formed in the flange projection from said front piece, said 20 spring intermediate its ends being coiled about the stud A¹⁸, upon which said lever is mounted. The rear end of the lever C⁴ has an arm C⁷ extending substantially at right angles to the main portion of said lever, and 25 this arm at its extremity is turned forward in a finger C⁸, bearing against the rear side of said front piece. A flat spring C⁹, mounted upon the stud A¹⁹, formed integral with said front piece, constitutes the detent device 30 for preventing accidental movement of said registering mechanism, for when said spring C⁹ is in its normal position it lies in the path of the finger C⁸ of the lever C⁴ and prevents the downward movement of said lever. A stud C¹⁰, fixed with relation to said 35 spring, constitutes the push-button hereinbefore mentioned and projects through the opening A⁹ in the front piece. In order to withdraw the spring from the path of the finger C⁸, it is only necessary to move the push-button inward, which movement withdraws the detent and releases the registering mechanism to action. The forward end of the lever C⁴ has three stages or portions C¹¹, C¹², 40 and C¹³, adapted to receive the "cents," "nickels," and "dimes" keys, respectively. The portion C¹¹, which receives the cents-key is comparatively low, inasmuch as said lever need be depressed only a little distance in 45 order to cause a sufficient movement of the cents-wheel. The plane C¹², which receives the nickels-key, is slightly higher than that which receives the cents-key and also is nearer the pivotal center of the lever. The plane 50 C¹³, which receives the dimes-key, is not only higher than that which receives the nickels-key, but also is nearer the pivotal center of

the lever. The forward end of the lever C⁴ carries a spring-pawl C¹⁴, the lower end of which is bent at right angles to its length and 55 lies in engagement with the ratchet-teeth of the cents-wheel. When the lever C⁴ is in its highest position, the free end of the pawl C¹⁴ lies between the teeth of the cents-wheel C and is held in such position by the fixed stop A²⁰, formed integral with the front piece, thus 60 preventing the forward movement of said wheel. A backward movement of the cents-wheel is prevented by the spring C¹⁵, secured upon the rear side of the front piece A⁶, the 65 forward end of which spring engages the ratchet-teeth of the cents-wheel C.

C¹⁶ is a plate for protecting the registering mechanism and for holding certain of the parts of said mechanism in position. This 70 plate is provided with three openings, by means of which it is held in place. One of these openings receives the stud A¹⁸, another the stud A²¹, and the third opening coincides with the screw-threaded opening in the stud A²⁴, the shoulder at the upper end of the screw-thread upon the pin A²⁵ holding the plate upon said studs. The stud A²², formed integral with and projecting from the rear 75 face of the front piece A⁶, supports one of the upper corners of the plate C¹⁶.

The locking mechanism for retaining the front piece in position comprises a box-loop D, secured to and rising from the inner side of the rear wall of the receptacle and having 80 the perforation D' near its center. Two flat springs D² and D³, their planes being at right angles to the rear wall of the receptacle A, are secured to the lower side of said box-loop, 85 their free ends being adapted to lie within the groove A²⁷, formed upon the locking-pin A²⁵. The pin being conical at its forward end may 90 easily be inserted into the opening D' and will pass the springs D² and D³; but as soon as the groove in the pin is coincident with the springs 95 the latter will press into said groove and prevent the withdrawal of the pin, and as said pin is secured within its threaded opening in the rear side of the front piece A⁶ the front 100 piece is thereby locked in position.

To permit access to the receptacle, a key D⁴ is provided, having oppositely-extending wards D⁵, which when inserted through the opening A²⁹, provided in the rear wall for its 105 reception, and said key is turned, force apart the free ends of the springs D² and D³, withdrawing said springs from the groove A²⁷ in the locking-pin A²⁵, and thus releasing said pin and the front piece.

In operation a deposit is made by dropping the desired amount into the receptacle through the opening A²⁸ in the top thereof. The push-button C¹⁰ is then depressed and the registering mechanism operated by means of the keys B, B', or B² until the amount of 110 the deposit has been registered. If the deposit was one cent, the push-button is depressed and the cents-lever pushed downward as far as possible and released. The spring- 115

pawl C¹⁴ at the forward end of the pivoted lever C⁴ travels downward with the depression of said lever, its free end passing over one ratchet-tooth of the cents-wheel C. When 5 the cents-key is released, the spring C⁵ raises the lever C⁴, rotates the cents-wheel C the distance of one tooth, and registers the deposit by moving the dial with relation to the cents-opening A⁷ in the front piece. If the deposit 10 is five cents, the cents-key may be depressed five times or the nickels-key once. In either event the spring-pawl C¹⁴ at the outer end of the lever C⁴ is caused to pass over five teeth in the periphery of the cents-wheel and to 15 move said wheel five steps, which will be indicated by the higher numbers which will coincide with the opening A⁷ in the face of the front piece. If a dime is to be registered, the cents-key may be depressed ten times, the 20 nickels-key twice, or the dimes-key once, the action of the mechanism being the same in either case. When the cents-wheel passes from "99" to "0," the projection on said wheel engages one of the peripheral teeth of the dollars-wheel and causes said wheel to be moved 25 the distance of one of its teeth. This causes the dollars-wheel to present the next higher figure at the opening A⁸ in the front piece A⁶.

The push-button C¹⁰ is placed at a little distance 30 from the registering-keys, so that said button shall not be depressed and the keys operated inadvertently or by accident.

It is obvious that two wheels representing cents and dimes having ten teeth each and 35 adapted to engage at suitable intervals might be substituted for the cents-wheel herein shown.

I am aware that many slight changes may be resorted to in the general form and arrangement 40 of the several parts described without departing from the spirit and scope of my invention, wherefore I desire to have it understood that I do not limit myself to the exact details herein shown and described, but 45 claim all such changes and modifications as properly fall within the scope and spirit of my invention.

I claim as my invention—

1. In a registering-bank, in combination, a 50 money-receptacle having a removable side; registering-keys mounted on said receptacle; a rotatable cents-wheel having a series of teeth and a projection; a pivoted lever adapted to be engaged at different distances from 55 its pivotal center by the registering-keys; a pawl on said lever adapted to engage the teeth on said cents-wheel; a dollars-wheel adapted to be engaged by the projection on said cents-wheel; and a movable detent adapted to prevent 60 the movement of said lever.

2. In a registering-bank, in combination, a 65 money-receptacle; registering-keys mounted on said receptacle; a rotatable cents-wheel having a series of teeth and a projection; a pivoted lever adapted to be engaged at different distances from its pivotal center by the registering-keys; a spring for moving said

lever in one direction; a pawl on said lever adapted to engage the teeth on said cents-wheel; a dollars-wheel adapted to be engaged by the projection on said cents-wheel; and a fixed stop adapted to hold said pawl between the teeth of said cents-wheel in order to prevent the forward movement of said wheel. 70

3. In a registering-bank, in combination, a 75 money-receptacle; registering-keys formed from spring material and secured at one end to said receptacle; a rotatable cents-wheel having a series of teeth and a projection; a pivoted lever adapted to be engaged at different distances from its pivotal center by the registering-keys; a spring for moving said lever in one direction; a pawl on said lever adapted to engage the teeth of said cents-wheel; a fixed stop adapted to hold said pawl 80 between the teeth of said cents-wheel to prevent the forward movement of said wheel; a dollars-wheel adapted to be engaged by the projection on said cents-wheel; and a spring adapted normally to engage a portion of said 85 pivoted lever to prevent the accidental movement of the registering mechanism.

4. A money-receptacle for registering-banks comprising integral sides and top, the sides being provided with bottom flanges; an integral bottom and back piece, the back having side flanges and a top flange; means for securing the bottom to the bottom flanges, the sides to the side flanges, and the top to the top flange; a standing loop on the inner 90 side of said back piece, said loop being provided with an opening therein; a front piece; a pin secured to said front piece adapted to enter the opening in said standing loop; and a spring-finger secured to said loop adapted 95 to engage said pin.

5. A money-receptacle for registering-banks comprising integral sides and top, the sides being provided with bottom flanges; an integral bottom and back piece, the back having side flanges and a top flange; means for securing the bottom to the bottom flanges, the sides to the side flanges, and the top to the top flange; a standing loop secured to the inner side of said back piece, said loop 100 being provided with an opening; a front piece; a pin having a conical head and a groove, which pin is adapted to enter the opening in said standing loop; and two spring-fingers adapted to engage the groove in said 105 pin to hold the front piece in position.

6. In a registering-bank, in combination, a money-receptacle; registering-keys in flat spring form, said keys being secured at one end upon the inner side of a wall of said receptacle; and registering mechanism in said receptacle, adapted to be operated by the movement of said keys. 115

7. In a registering-bank, in combination, a 120 money-receptacle; registering-keys mounted on said receptacle; a rotatable cents-wheel having a series of teeth and a projection; a pivoted L-shape lever having different planes adapted to be engaged by the registering- 125

keys; a spring for moving said lever in one direction; a movable detent-spring adapted to engage the other arm of said L-shape lever to prevent the movement of said lever; a 5 pawl on said lever adapted to engage the teeth of said cents-wheel; and a dollars-wheel adapted to be engaged by the projection on said cents-wheel.

8. In a registering-bank, in combination, a 10 money-receptacle; registering-keys; a registering mechanism adapted to be operated by said registering-keys, said mechanism comprising a pivoted L-shape lever; a detent-spring adapted to prevent the movement of 15 said lever; and a push-button for moving said detent-spring.

9. In a registering-bank, in combination, a 20 money-receptacle having a removable side, said side being provided with a dollars-opening, a cents-opening, and a push-button opening; registering-keys mounted on said receptacle; a cents-wheel having a series of teeth and a projection, said wheel being ro-

tatably mounted upon said removable side; a pivoted L-shape lever adapted to be engaged at different distances from its pivotal center by the registering-keys, which lever is mounted upon said removable side; a spring for holding said lever in one direction; a pawl on said lever adapted to engage the 25 teeth on said cents-wheel; a stop projection on the removable side adapted to hold said pawl in engagement with the teeth of said wheel to prevent the forward movement of the wheel; a dollars-wheel adapted to be engaged by the projection on said cents-wheel; a detent-spring normally lying within the 30 path of movement of a portion of said lever; and a push-button extending through the push-button opening in the removable side, 35 by means of which the detent is withdrawn.

WILLIAM WEBER.
